EGG CASE FILLER

Desmond Karl Swager, Los Angeles, Calif.,
assignor to Leon Benoit, Chicago, Ill.

Application May 15, 1931. Serial No. 537,702

15 Claims. (Cl. 217—33)

The present invention is directed to receptacles, and more particularly to a filler of the honeycomb type for egg cartons or the like.

One of the objects of the invention is to provide a filler of simple construction, which will effectively protect the brittle contents against destruction from rough handling.

Another aim is to provide a filler or holder of the type indicated, which is preferably collapsible, yet easy to assemble, light in construction and dependable in use.

Still a further aim is to provide a filler or holder with means constituting a continuation of its side walls to form a bottom and supporting ridge, and which is adapted to maintain the eggs or other contents in spaced relationship to the walls of the container into which the filler or holder may be inserted.

Other objects will be in part obvious and in part pointed out hereinafter.

The invention will be understood from the description hereinafter appearing, taken in connection with the drawing, which shows one embodiment thereof, and in which the same reference characters designate the same parts in the different views.

In the drawing—

Fig. 1 is a perspective view of my improved filler showing the same fully assembled.

Fig. 2 is a side elevation of the slotted blank constituting one of a plurality of transverse walls.

Fig. 3 is an end view of the assembled filler shown in Fig. 1.

Fig. 4 is a perspective view similar to Fig. 1, but with the filler inverted to more clearly show the bottom construction thereof.

Fig. 5 is an elevational view, broken away, of the blank which forms the combined side wall, bottom and supporting ridge of the filler.

Fig. 6 is an elevational view showing my improved filler when collapsed.

The invention comprises a pair of similar blanks 10, 10^a, each constituting in assembled condition a side wall, one-half of a bottom 11, 11^a and a supporting ridge of my filler F. It will be noted by reference to Fig. 5 that each of the blanks 10, 10^a is characterized by three parallel score lines 12, 12^a, 12^b about which the blank is folded to form the aforementioned bottom and ridge.

In order to permit the transverse walls 13 to be interlocked therewith, each of the blanks is formed with a plurality of transversely spaced slots 14, 14^a, etc., for receiving the tapered portions 15 of the transverse walls 13; also with a plurality of slots 16, 16^a, etc. having lugs 17 for locking

within inverted T-shaped apertures 18, 18^a in the transverse walls.

In addition to a pair of side walls and a plurality of transverse walls, each filler is distinguished by an intermediate wall 19 having lugs 20 for interlocking engagement within the central inverted T-shaped slot 18^b in each of the transverse walls 13.

In assembling the filler, the intermediate wall 19 may be connected with a plurality of the walls 13 by insertion into the flared mouth 21 of the latter, which it will be seen, is continued in the form of an elongated slit 22. When so assembled, the wall 19 sinks well within the slit and the lugs 20 are positioned in locked condition 70 within the slots 18^b. The width of the blank 13 is materially greater than the blank constituting the intermediate wall, so that when in operative position, the wall 19 is spaced from the top and bottom edges of the wall 13. 75

The side walls are each placed in position by insertion through the flared openings 21^a, 21^b, respectively, of the transverse walls 13, until the lugs 17 engage within the inverted slots 18, 18^a. The blank is then folded on its score lines so 80 that the slots 14, 14^a etc. receive therethrough the tapered portions 15, while the edge 23 of each blank is folded on the score line 12 to constitute a vertical ridge portion 24 inserted through the opening 21 to rest on the intermediate wall 19. 85 In view of the fact that the two side walls are similar, and each is characterized by an edge 23, the two vertical ridge portions 24 will be in abutting relationship. Consequently, the entire filler in its upright position will rest on the edges 25 90 and 26 of the transverse walls and on the edges 27 of the ridges 24. The bottom of each cell, as will be apparent, is trough-shaped, and an egg or similar article will accordingly be held in spaced relationship with respect to another container into which the filler may be inserted. 95

By reference to Fig. 6, it will be noted that when the side walls are not folded on the scored lines into position, the filler may be collapsed. 100

From the above description it will be seen that I have constructed a filler or holder formed of two similar blanks constituting combined side and bottom closure walls and a supporting ridge, an intermediate blank dividing the filler into cells and a plurality of similar blanks constituting transverse walls. In view of the fact that the trough-shaped bottom of each cell is spaced above the edges 25 and 26 of the walls 13 and the edges 27 of the ridges 24, an egg placed in a cell 110

will be effectively spaced from the walls of a container in which the filler may be inserted.

Various other advantages of the invention will be apparent, without further discussion, and it is my intention to cover any changes which may be made in the specific embodiment shown, and to be limited in this respect only as may be necessary by the scope of the claims appended hereto.

I claim:

10. 1. A filler for cartons and the like comprising a pair of similar blanks having slots therein and foldable to form side walls, a bottom and a supporting ridge; transverse walls and an intermediate wall engageable therewith, the slots of the blanks adapted to receive a portion of the transverse walls therethrough.

20. 2. A filler for cartons and the like comprising a pair of scored and slotted blanks foldable to form side walls, a bottom and a supporting ridge, and a plurality of transverse walls receivable through the slots of the blanks.

25. 3. A filler for cartons and the like comprising a pair of similar scored blanks having transverse slots and locking means, said blanks foldable to form side walls, a bottom and a supporting ridge, and a plurality of similar slotted transverse walls adapted to receive the locking means through its slots, and the slots of the blanks receiving a portion of the walls therethrough.

30. 4. A filler for cartons and the like comprising a pair of similar slotted blanks each scored to form a side wall, a trough-shaped bottom, and a supporting ridge; an intermediate wall, and a plurality of transverse walls for interlocking engagement with the blanks and intermediate wall to form a plurality of cells.

35. 5. A filler for cartons and the like comprising a pair of similar blanks foldable to form side walls, a bottom and a ridge, a plurality of transverse walls interlocked with the blanks and an intermediate wall resting within the transverse walls, said ridge receivable within the transverse walls for contacting engagement with an edge of the intermediate wall.

40. 6. In a filler, the combination of interconnected intersecting longitudinal and transverse walls forming a unitary collapsible cellular filler, and two bottom walls, each angled to provide a trough with opposite edges elevated having adjacent portions in supporting engagement with a common longitudinal wall and their remote edges connected detachably to a transverse wall whereby to provide raised suspension for articles rested within the troughs of the filler bottom, the 45 walls when so positioned serving to resist collapse of the filler.

45. 7. In a filler, the combination of a series of transverse vertical walls intersected by a longitudinal central wall which is interlocked with the others in a manner to be maintained in a vertical plane withal permitting swinging of the transverse walls to a collapsed condition, one upon another and all upon the longitudinal wall, and a bottom wall angled to provide two troughs each with opposite edges elevated and having adjacent portions in supporting engagement with the central longitudinal wall and their remote edges connected detachably to a transverse wall whereby to provide raised suspension for articles 50 rested within the troughs of the filler bottom.

70. 8. A collapsible container having a plurality of cross walls intersected by a plurality of longitudinal partitions all interlocked to form a unitary cellular structure, and means providing a cushion closure for each cell consisting of a wall

extending along a row of cells between two of the partitions and having one edge turned to lie parallel with one such partition adjacent an edge thereof with which it is supportingly engaged, the closure wall extending away from said partition at a point remote from said partition edge angularly toward the other partition and in regressively spaced relation to the plane of said partition edge whereby the closure wall is disposed non-transversely across one open end of each container cell.

80. 9. A filler for cartons and the like comprising a plurality of cross walls swingingly joined to a central longitudinal partition whereby to provide a collapsible unitary structure defining a plurality of cells, and closure walls one for each row of cells extending oppositely from the central partition, each closure wall being bent along a line adjacent the partition to provide a strip which extends parallel with the partition a distance sufficient to present the strip edge in substantially the same plane with the remaining filler walls and engaging with the partition in a manner to furnish support therefor, each closure wall extending non-transversely from the 100 partition in an angular direction which approaches the plane aforesaid and disposed between the cross walls in a manner to resist collapse of the filler, the closure walls being movable to positions from between the cross walls 105 whereby to permit the filler to collapse freely.

10. A collapsible container having a plurality of cross walls intersected by a plurality of longitudinal partitions all interlocked to form a unitary cellular structure, and cell closure means 110 consisting of a wall extending along a row of cells disposed between two of the partitions and of a width greater than the distance between such two partitions requiring the wall to lie angularly therebetween, one edge of the wall being 115 turned to extend parallel with the proximate partition and having supporting engagement therewith.

11. A collapsible container having a plurality of cross walls intersected by a plurality of longitudinal partitions all interlocked to form a unitary cellular structure, and cell closure means consisting of a longitudinal wall extended between the partitions and angled to provide a trough with elevated portions adjacent the partitions, one edge of the angled wall being downturned for engagement with a plane surface in coincidence with the remaining bottom engaging edges of the container, and the opposite edge of the angled wall being upturned and connectible with a cross wall.

12. A filler comprising interconnected intersecting longitudinal and transverse walls forming a collapsible cellular structure, and bottom walls oppositely inclined with respect to each other and extending between the transverse walls, said bottom walls having adjacent folded down portions in supporting engagement with a common longitudinal wall, whereby to provide raised suspension for articles rested upon 140 the filler bottom.

13. A filler comprising a plurality of slotted cross walls intersected by a longitudinal partition, said cross walls and partition having interlocking means whereby they may be folded flat 145 without separation, and a bottom strip slotted transversely to extend between adjacent cross walls, said strip being folded down longitudinally to provide a bottom supporting portion extending longitudinally of the filler through the lower 150

slotted ends of the cross walls adjacent said partition.

14. A filler comprising a plurality of slotted cross walls and partitions interfitted to provide 5 rows of cells each having four side walls, and means providing an inclined bottom wall for each cell, comprising a foldable strip bent down longitudinally of the filler to provide a vertical, bottom supporting portion paralleling a partition 10 and extending to the lower edge of the cross walls through which it extends, said strip being slotted transversely from said supporting portion to receive said cross walls and extend there-between and between the walls provided by the 15 partitions.

15. A filler comprising a plurality of cross walls each slotted to receive a central partition and two side partitions, means interlocking said cross walls and partitions to provide two rows of cells each having four side walls, and means providing a bottom wall for each cell oppositely inclined from said central partition and between adjacent cross walls comprising a transversely slotted strip folded down adjacent said central partition to the lower edge of the cross walls to 85 provide a vertical bottom supporting portion, said portion extending longitudinally of the filler through the slots of the cross walls.
